MOUTHPIECE FOR BOTTLES

Ivan J. Wershay, Cicero, Ill.

Application February 4, 1933, Serial No. 655,275

2 Claims. (Cl. 215—100)

The present invention relates to an attachment for bottles and more in particular to a mouthpiece adapted to be readily and easily applied to the mouth or neck of a bottle and thereby form a sanitary drinking device.

Among the objects of the present invention is to provide a mouthpiece constructed of sanitary paper, fabric or other material which can be manufactured very cheaply and readily applied to the mouth or neck of a bottle to permit a person to drink the contents thereof without the lips touching the bottle. In the usual method of dispensing soft drinks or other liquid sold in the bottle for consumption at the place of sale, it frequently happens that individual glasses or containers are not supplied and the purchaser must drink directly from the bottle. Such bottles are seldom sanitary and thus there is always present the danger of the purchaser contracting a disease. The present invention will eliminate this danger due to the fact that no part of the neck or mouth of the bottle will be exposed to or in direct contact with the lips of the purchaser.

Another object of the invention is the provision of a mouthpiece which can be cheaply and readily made, and which because of such cheapness can be discarded after it has been once used. Due to the extreme cheapness of this construction, the manufacturer or retailer need add no additional charge to his product.

A still further object of the invention is the provision of a mouthpiece constructed of liquid-proof or liquid-repellant material such as wax paper or other treated paper or fabric which is substantially rigid and remains so during the period that the contents of the bottle are being consumed.

Yet another object of the invention is the provision of a novel drinking or dispensing mouthpiece, and in the shape and contour thereof which greatly facilitates drinking or pouring of the contents of the bottle. If desired, the novel mouthpiece may be provided with advertising matter thereby adding to or enhancing the value of the product to the manufacturer and/or retailer.

Further objects of the invention are to provide a construction of maximum simplicity, efficiency, economy and ease of assembly and operation, and such further objects, advantages and capabilities as will later more fully appear and are inherently possessed thereby.

The invention further resides in the combination, construction and arrangements of parts illustrated in the accompanying drawing, and

while there is shown therein a preferred embodiment, it is to be understood that the same is susceptible of modification and change, and comprehends other details and constructions without departing from the spirit of the invention. 5

Fig. 1 is a fragmentary view, part in front elevation and part in vertical cross section of the novel mouthpiece as applied to a bottle.

Fig. 2 is a fragmentary view in side elevation thereof. 10

Fig. 3 is a plan view of the device.

Fig. 4 is a view similar to Fig. 1 but disclosing an alternate construction.

Fig. 5 is a view in side elevation of the embodiment shown in Fig. 4. 15

Fig. 6 is a view similar to Fig. 5 but showing a further alternate construction.

Fig. 7 is a fragmentary view part in side elevation and part in vertical cross section of an embodiment similar to Figs. 1, 2 and 3 as applied to 20 a milk bottle and provided with a flap or closure.

The present novel sanitary mouthpiece as embodied in Figs. 1, 2 and 3, comprises a member 1 constructed of some liquid-proof or liquid-repellant material such as wax paper, or other fabric or material suitable for the purpose. Adjacent one end thereof the member is crimped or indented as at 2 to provide a shoulder or abutment 3, and the end thereof is formed as an annular corrugation or bead 4 having its outer or 30 lower edge rolled as at 5. The opposite end of the member is formed with a slanted opening 6 providing an outlet for the contents of the bottle, said opening having a straight edge joined by a curved edge. Throughout a considerable portion 35 of its length the member tapers as at 7 whereby to provide a flat lip, the outer extremity of which constitutes the straight edge of said opening 6. The edge formed by said flap lip projects beyond the plane of the curved edge of the opening 6 in 40 such manner that while the bottle is held in drinking position, the said slanted opening will provide clearance for the drinker's lips, i. e. the flat side will contact with the lower lip of the drinker and the curved edge will provide clearance for his upper lip. Due to this tapering, the mouthpiece is shaped to fit the mouth of the consumer and permits drinking in the same manner as drinking from a glass, thus eliminating the necessity of tilting the head back as is done when 45 drinking direct from a bottle.

When the mouthpiece is slipped over the bottle 8, the bead 4 will encompass the upper bead 9 on the bottle and the shoulder 3 will abut the edge 10 of the neck of the bottle and thus limit and 55

position the mouthpiece in place. The attachment is very simple and readily accomplished.

In Figs. 4 and 5 is disclosed an alternate construction of mouthpiece 11 in which the outlet or opening 6^a and tapered portion 7^a is quite similar to that disclosed in Fig. 1, although the contour of the body portion differs slightly over the prior form. In this embodiment, the lower end of the member is crimped as at 12 and this crimped portion seats below the bead 9 on the bottle.

In Fig. 6 is shown a further alternate construction in which the body of the member 11 is similar to that disclosed in Fig. 4 with the exception that it is provided with a double crimped portion as at 13, 14, with an intermediate bead 15 adapted to seat on the upper or lower bead of the bottle where it is provided with a pair of beads. This form also provides additional contact area between the mouthpiece and bottle whereby to prevent its ready displacement.

In Fig. 7 is disclosed a form similar to that shown in Fig. 1 as applicable for attachment to a milk bottle 16 in which the member 17 is provided with a crimped portion 18 and at its one end with a bead 19 having a rolled edge 20, the bead being adapted to receive the bead or rim 21 on the bottle. At its opposite end, the mouthpiece is provided with a tapered lip 22 leading to a slanted opening or outlet 23 adapted to be closed by a flap or closure 24. In this form the outlet is disposed opposite to that in the remaining views to permit easy pouring of the contents. It is to be understood that any of the structures shown could be provided with such a closure if desired. This form would be extremely practical as a spout and closure for milk bottles or other liquid containers.

From the above it will be clearly seen that the invention comprises a novel and practical construction of sanitary mouthpiece for bottles, one which can be made very cheaply and easily applied to various forms of bottles, and which permits easy drinking from a bottle without danger 45 of infection.

Having thus disclosed the invention, I claim:

1. A sanitary mouthpiece for temporarily facilitating drinking from a bottle which is provided with a bead contiguous to its mouth, said mouthpiece consisting of a tubular body of liquid-proof material having an open base at one end provided with a crimped portion complementary to said bead for anchoring the mouthpiece in place, said body having a slanted opening at the other end thereof, said opening having a straight edge joined by a curved edge, one side of said body being flat and tapered in such manner that the outer extremity thereof constitutes the straight edge of the opening and projects beyond the curved edge thereof, said tapered side and the edges of said opening being so constructed and arranged that while the bottle is in drinking position, the slanted opening in said mouthpiece provides clearance for the lips of the drinker, and the edge of said flat side of the body will contact with his lower lip.

2. A sanitary mouthpiece for temporarily facilitating drinking from a bottle which is provided with a bead contiguous to its mouth, said mouthpiece consisting of a tubular body of liquid-proof fibrous material having an open base at one end provided with a crimped portion complementary to said base and anchoring the mouthpiece in place, said body being indented so as to overlie the edge of the bottle mouth, said body also having a slanted outlet opening at the other end thereof, said opening having a straight edge joined by a curved edge, one side of said body being flat and tapered in such manner that the outer extremity thereof constitutes the straight edge of the opening and projects beyond the curved edge of said opening, said tapered side and the edges of said opening being so constructed and arranged that while the bottle is in drinking position the slanted opening in said mouthpiece provides clearance for the lips of the drinker, and the edge of said flat side of the body will contact with his lower lip.

IVAN J. WERSHAY. 45
